(74) **Attorney, Agent, or Firm:** Quarles & Brady LLP

(57) **CLAIM**

The ornamental design for a videoconferencing unit, as shown and described.

DESCRIPTION

FIG. 1 is an isometric view of a top, front, and right side of an ornamental design for a first embodiment of a videoconferencing unit;

FIG. 2 is a top plan view thereof;

FIG. 3 is a bottom plan view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is an isometric view of a top, front, and right side of an ornamental design for a second embodiment of a videoconferencing unit;

FIG. 9 is a top plan view thereof;

FIG. 10 is a bottom plan view thereof;

FIG. 11 is a front elevational view thereof;

FIG. 12 is a rear elevational view thereof;

FIG. 13 is a left side elevational view thereof; and,

FIG. 14 is a right side elevational view thereof.

The dash-dash-dash lines illustrate portions of the videoconferencing unit that form no part of the claimed design.

1 Claim, 9 Drawing Sheets
